GARMENT POCKET STRUCTURE

Melvin L. Bacharach, San Rafael, Calif., assignor to Levi Strauss and Company, San Francisco, Calif.

Filed Apr. 27, 1959, Ser. No. 809,239

4 Claims. (Cl. 2—248)

This invention relates to a garment construction and more particularly to an improved pocket structure for a garment.

The main object of the invention is the provision of a novel pocket structure in which the pocket opening is provided with a flap covering said opening and flush with the shell of the garment to effect a neat appearance.

Another object of the invention is the provision of a pocket structure which is reinforced so as to prevent sagging of the pocket opening even after a long period of use.

Still another object of the invention is the provision of a pocket structure that includes a flap closing the pocket opening to prevent loss of the contents of the pocket, and which flap does not interfere with access to the pocket.

Other objects and advantages will be seen from the following specification and from the drawings.

Fig. 1 is a fragmentary elevation of a portion of the shell of a garment showing a pocket formed therein in accordance with the invention;

Fig. 2 is a view similar to Fig. 1 with portions of the shell and pocket structure broken away for clarity.

Although the invention is adapted to be employed with any type of pocket it will be described herein as applied to the hip pocket of a pair of trousers, in which application it is used to greatest advantage.

The shell 1 of the garment is cut along a line representing the longitudinal centerline of the pocket opening and is folded to provide a hem 2 (Fig. 2) along the upper margin of the opening and a hem 3 along the lower margin. The pocket opening is preferably in the shape of an elongated rectangle and the corners may be squared by making divergent cuts at the ends of the pocket opening to provide a pair of triangular tabs 5, 6 (Fig. 1) which are folded over and stitched to the shell.

As best seen in Fig. 1 the finished pocket opening is thus provided with spaced longitudinally extending upper and lower edges 8, 9 and opposite end edges 10, 11.

The pocket proper is formed of two sections 15, 16 of pocketing material stitched together along their edges as indicated at 14. A welt, generally designated 17, is formed of a section of shell material and is folded over and stitched to the lower margin of the pocket. As seen in Fig. 2 the inner section 15 of the pocket is preferably provided with an extension 18 which is extended in lapping relation to the welt material and is folded over with the latter to provide a reinforced welt of four thicknesses of material. The inner edge of the welt material is preferably hemmed as indicated at 20 before the welt is stitched to the shell 1 at its hem 3.

It should be noted at this point that the reinforced welt 17 extends upwardly toward the upper marginal edge 8 of the pocket opening and lends rigidity to the pocket structure resisting the tendency of the pocket to sag under the weight of its contents. Such resistance to sagging is further enhanced by the fact that the welt is

2

stitched to the shell by bar tacks 22, 23 (Fig. 1) and continues horizontally to the vertical side edges of the pocket proper and is stitched thereto by the pocket stitching 14. Furthermore, the inner section 16 of the pocket extends upwardly past the pocket opening and is stitched to the waistband of the trousers as by stitching 25 (Fig. 2).

To cover the welt 17 and to give the pocket a finished appearance a flap 30 is provided covering the pocket opening and overlying the welt 17. Said flap 30 comprises a folded over section of material stitched to the shell along the margin of upper side edge 8. The flap 30 is positioned so that the fold line 31 defining the lower edge of the same is in substantially meeting relationship with the lower edge 9 of the pocket opening. The same line of stitching 33 that secures the hem 2 to the shell 1 may also be used to secure the double thickness of material that constitutes the flap 30. Also the stitching 33 may be employed to secure the inner section 16 of the pocket to the shell.

Interposed between the welt 17 and the inner pocket section 16 is a section of pocket facing 35 which may be hemmed as at 36 and stitched to the inner pocket section as at 37 and secured to the said section and to the shell 1 by the above mentioned row 33 of stitching. If the pocketing material is of the same fabric as the shell 1, facing 35 may be omitted since its primary function is to hide the pocketing material when the pocket is opened. However, the facing, when used, assists in adding rigidity to the pocket structure.

The flap 30 is provided with a row of stitching 38 adjacent the fold line 31 to provide reinforcement of the same and enhance its resistance to wear.

The above described structure provides a neat appearing pocket because the flap 30 is an integral part of the pocket itself and is, at the same time, flush with the shell 1.

Fabrication is relatively simple, and it will be noted in this connection that a subassembly that includes the pocket sections 15, 16, the facing 35 and the welt 17 may be fabricated as a separate operation before final assembly with the flap 30 and welt 17.

The above specific description of the preferred embodiment of the invention is not to be taken as restrictive of the same as various modifications will occur to those skilled in the art without departing from the spirit of the invention.

I claim:

1. A pocket structure for a garment comprising: a garment shell provided with an elongated pocket opening having a pair of longitudinally extending elongated margins and a relatively narrow width compared to its length, a welt secured to said shell along the inner side of one of the elongated margins of said opening and having a free end extending toward the other elongated margin, a flap secured to said shell along the inner side of said other margin and extending toward said one margin and outwardly of and in overlying relationship relative to said welt for closing said opening and substantially covering said welt from view from the outer side of said garment, and a pocket secured at one of its sides to said one margin and at its other side to said other margin.

2. A pocket structure for a garment comprising: a garment shell provided with an elongated pocket opening having a pair of longitudinally extending elongated margins and a relatively narrow width compared to its length, a welt secured to said shell along the inner side of one of the elongated margins of said opening and having a free end extending toward the other elongated margin, a flap secured to said shell along the inner side of

said other margin and extending toward said one margin and outwardly of and in overlying relationship relative to said welt for closing said opening and substantially covering said welt from view from the outer side of said garment, and a pocket secured at one of its sides to said one margin and at its other side to said other margin, said flap comprising a section of fabric folded on itself with the fold of said section adjacent said one margin, a row of stitches along said fold for reinforcing the same.

3. A pocket structure for a garment comprising: a garment shell provided with an elongated pocket opening having a pair of longitudinally extending elongated margins and a relatively narrow width compared to its length, a welt secured to said shell along the inner side of one of the elongated margins of said opening and having a free end extending toward the other elongated margin, a flap secured to said shell along the inner side of said other margin and extending toward said one margin and outwardly of and in overlying relationship relative to said welt for closing said opening and substantially covering said welt from view from the outer side of said garment, and a pocket secured at one of its sides to said one margin and at its other side to said other margin, said welt comprising a section of fabric folded on itself with the fold of said section adjacent said other margin, said one side of said pocket extending along-

side the inner side of said folded welt fabric to provide four thicknesses of material in said welt to prevent sagging of said pocket at said one margin.

4. A pocket structure for a garment comprising: a garment shell provided with an elongated pocket opening having a pair of longitudinally extending elongated margins and a relatively narrow width compared to its length, a welt secured to said shell along the inner side of one of the elongated margins of said opening and having a free end extending toward the other elongated margin, a flap secured to said shell along the inner side of said other margin and extending toward said one margin and outwardly of and in overlying relationship relative to said welt for closing said opening and substantially covering said welt from view from the outer side of said garment, and a pocket secured at one of its sides to said one margin and at its other side to said other margin, said flap comprising a section of fabric folded on itself with the fold of said section adjacent said one margin.
